United States Patent

Des. 238,233

Patented Dec. 30, 1975

238,233

PILLOWED SLING CHAIR BODY

Gerry D. Welton, 910 E. Tripp, Peoria, Ill. 61603

Filed Oct. 12, 1973, Ser. No. 405,929

Term of patent 14 years

Int. Cl. D6—06

U.S. Cl. D6—197

FIG. 1

FIG. 2

FIG. 3

FIG. 4

FIG. 1 is a front perspective view of a pillowed sling chair body embodying my new design.

FIG. 2 is a rear perspective view of the pillowed sling chair body shown in FIG. 1.

FIG. 3 is a side elevation of the pillowed sling chair body shown in FIGS. 1 and 2.

FIG. 4 is an extended plan view of the pillowed sling chair body shown in FIG. 1, FIG. 2 and FIG. 3.

I claim:

The ornamental design for a pillowed sling chair body, as shown.
